Inventor
Marco Marinelli
by Horatio E. Bellows
Attorney

UNITED STATES PATENT OFFICE

MARCO MARINELLI, OF PROVIDENCE, RHODE ISLAND

FINGER RING

Application filed May 21, 1930. Serial No. 454,235.

My invention relates to finger rings of the type wherein a stone or other ornament is carried in an enlarged head.

Heretofore this type of ring has been excessively expensive because of the great mass of material concentrated in the solid head, especially when, as is usual, the material is of precious or semiprecious material. The essential objects of my invention are to diminish the amount of material; to employ a minimum of parts; to facilitate the assemblage of parts; and to attain these ends in a strong, simple, inexpensive and sightly structure.

To the above ends essentially my invention consists in such parts and in such combinations of parts as fall within the scope of the appended claims.

In the accompanying drawings which form a part of this specification,

Figure 1 is a side elevation of a ring embodying my invention,

Figure 2, an end elevation,

Figure 3, a section of the same taken on line 3—3 of Figure 2,

Figure 4, a section taken on line 4—4 of Figure 3, and

Figures 5, 6 and 7, detailed perspective views respectively of the cup annulus and setting.

Like reference characters indicate like parts throughout the views.

My ring includes an annulus 10 provided with a laterally enlarged upper portion or bearing 11 tapering inwardly to its junction with the lower portion or shank 12 of the ring. The top portion is provided with a central opening 13. The entire exterior surface of the enlarged portion 11 is cut away or otherwise externally reduced in thickness forming a recess 16 with resultant end abutments 17 adjacent the shank portion of the ring. Superposed upon the portion 11 is an upwardly tapering cap or housing member 18 comprising a substantially horizontal top wall 19 provided with a central orifice 20; upwardly tapering or oppositely inclined side walls 21 having longitudinally arcuate lower edges 22; and upwardly tapering oppositely inclined end walls 23 terminating in down-

wardly directed transversely tapering extending portions 24 having terminal horizontal edges 25. The edges 22 of the cap rest upon the lateral margins of the recessed bearing portion 11 of the annulus flush with the edges of the latter. The cap edges 25, also in the recess 16, engage the abutments 17 with the exterior faces of the extension portions 24 flush and continuous with the external portions of the annulus adjacent the shank. All of the bottom edges of the cap are secured to the annulus by solder.

The opening 13 conforms in shape to that of the orifice 20, but it is of less diameter than the former. A box setting includes a body 28 in whose upper portion is an internal shoulder 29 at the base of a terminal retaining flange 30, adapted to clamp a gem, stone, or other ornament 31 upon its seat 29. The setting body 28 conforms transversely with the shape of the opening 13 and orifice 20, and, extending through the latter, rests upon the bearing 11 with its inner face flush with the bounding edge of the opening. The end walls of the setting body have longitudinally curved lower edges 33 to conform to the curvature of the bearing face 11. The upper portion of the setting body is fixed by solder or otherwise, as at 36, to the housing member 18. The latter combined with the setting body 28, which constitutes a partition, forms a substantially annular empty chamber space 38.

It will be observed that by virtue of the housing member 18, completed by the partition formed by the setting body 28, the head of the ring comprehends merely an empty chamber 38, thus avoiding the great mass of valuable material heretofore required in rings of this type, wherein the head or base was completely solid with the exception of the central hole therethrough for the admission of light to the ornament.

It will be also noted that the wall of the setting body 28 is utilized as a partition element in conjunction with the housing, so that in constructing the ring but three elements, exclusive of the ornament, are required, whereby labor expense is reduced to a minimum. The housing seat 16 formed upon the

exterior of the bearing 11 assists in positioning the housing, or cap, and affords unbroken flow lines upon the exterior ring surface at the points where the joints occur.

[5] I claim:—

- [5] 1. In a finger ring of the type set forth, an annulus comprising a broad bearing and a reduced shank, the bearing being provided with a central orifice, an upwardly tapering hollow housing inset upon the bearing and provided with a central opening in its top, a tubular setting member engaging the bearing around the orifice and engaging the housing in the opening at a point remote from the orifice, and an ornament supported by the setting member.
- [10] 2. In a finger ring of the type set forth, an annulus comprising a broad bearing provided with a central orifice, and a shank, a housing member inset upon the bearing comprising upwardly tapering walls, and a top wall integral with the first walls provided with a central opening having its center in vertical alignment with the center of the orifice, a setting member comprising a tubular body extending through the opening and engaging the bearing around the orifice, an internal seat in the body, and a terminal flange upon the body above the housing, and an ornament [15] in the seat and engaged by the flange.
- [20] 3. In a finger ring of the type set forth, an annulus comprising a broad bearing provided with a central orifice, and a shank, a housing member inset upon the bearing comprising upwardly tapering walls, and a top wall integral with the first walls provided with a central opening having its center in vertical alignment with the center of the orifice, a setting member comprising a tubular body extending through the opening and engaging the bearing around the orifice, an internal seat in the body, and a terminal flange upon the body above the housing, and an ornament [25] in the seat and engaged by the flange.
- [30] 4. In a finger ring of the type set forth, an annulus comprising a broad bearing provided with a central orifice, and a shank, a housing member inset upon the bearing comprising upwardly tapering walls, and a top wall integral with the first walls provided with a central opening having its center in vertical alignment with the center of the orifice, a setting member comprising a tubular body extending through the opening and engaging the bearing around the orifice, an internal seat in the body, and a terminal flange upon the body above the housing, and an ornament [35] in the seat and engaged by the flange.

In testimony whereof I have affixed my signature.

MARCO MARINELLI.
